UNITED STATES PATENT OFFICE.

MAX DOERFEL, OF KLINGENTHAL, GERMANY, ASSIGNOR TO C. F. DOERFEL,
STEINFELSER & CO., OF SAME PLACE.

HARMONICA.

SPECIFICATION forming part of Letters Patent No. 331,949, dated December 8, 1885.

Application filed April 16, 1885. Serial No. 162,442. (No model.)

To all whom it may concern:

Be it known that I, MAX DOERFEL, residing at Klingenthal, in the Empire of Germany, have invented a new and Improved Harmonica, of which the following specification is a full, clear, and exact description.

This invention relates to a novel construction of harmonica or mouth-organ, and more particularly to the manner of connecting the several parts which constitute the instrument.

The invention consists in the details of construction hereinafter more fully pointed out.

In the accompanying drawings, Figure 1 is a longitudinal section of my improved harmonica. Fig. 2 is a transverse section on the line x x , Fig. 1. Fig. 3 is a top view of the reed-plate. Fig. 4 is a longitudinal section of a modification; Fig. 5, a section on line y y , Fig. 4, and Fig. 6 a section on line x' x' , Fig. 4.

The letter a represents the upper plate, and b the lower plate, of a harmonica. c is the reed-plate interposed between them. Each of the plates a b is provided with a dovetailed mortise at its right and left edge, and when the two plates are placed upon each other their mortises communicate, as seen in Fig. 2.

d d are a pair of plugs, having shanks of double-dovetail form to fit within the mortises between plates a b . The plate c is notched opposite these plugs, and the plugs are of such length as to enter the notches. 30

In use the parts a b c are placed in proper position, and then the plugs d are inserted to bind them all together.

In Figs. 4, 5, and 6 I have shown U-shaped 35 clasps e , which embrace the edges of the plates a b .

I claim as my invention—

1. The combination, in a harmonica, of mortised plates a b and reed-plate c , with plugs d , substantially as specified. 40

2. The combination of mortised plates a b and notched plate c with the plugs d , having dovetail shanks, substantially as specified.

In testimony whereof I have signed my name 45 to this specification in the presence of two subscribing witnesses.

MAX DOERFEL.
